UNITED STATES PATENT OFFICE.

JOSEPH E. HAUSFELD, OF CINCINNATI, OHIO.

BURNER FOR FURNACES.

1,378,951.

Specification of Letters Patent.

Patented May 24, 1921.

Original application filed December 26, 1917, Serial No. 208,776. Divided and this application filed April 3, 1920. Serial No. 371,092.

To all whom it may concern:

Be it known that I, JOSEPH E. HAUSFELD, a citizen of the United States, and a resident of Cincinnati, in the county of Hamilton and State of Ohio, have invented certain new and useful Improvements in Burners for Furnaces, of which the following is a full, clear, and exact description, reference being had to the accompanying drawings, forming part of this specification.

My invention relates to burners for furnaces, primarily for melting brass and like alloys, which employ a direct heating with or without any separate crucible. This application is a division of my copending application Serial No. 208,776, filed December 26th, 1917.

It is my special object herein to provide a single heating unit for the use of either gas or oil as a fuel, in such a furnace so that at a moment's notice the gas can be turned off and liquid fuel substituted without in any way modifying or changing the apparatus. This is accomplished by utilizing an oil pump in connection with the blower for furnishing a proper mixture and forced draft when either gas or liquid fuel is used.

These objects and other advantages to be noted I accomplish by that certain construction and arrangement of parts to be hereinafter more specifically pointed out and claimed.

In the drawings, which illustrate one construction of my improved furnace as the preferable construction,

Figure 1 is a plan view of the heating unit for either oil or gas.

Fig. 2 is a side elevation of the same, partly in section, on the lines 2—2 of Fig. 1.

Fig. 3 is a detail elevation of the oil spray nozzle.

The furnace may be of any desired nature and a corner thereof is shown at 1 held in a trunnion 10 and barring a fuel inlet 31.

Mounted on a bracket 39 secured to the standard 12 is a blower casing 26 for maintaining a proper gas mixture and the necessary forced draft, the gas being supplied through the gas inlet pipe 33. The outlet pipe 27 from the blower is connected to the trunnion extension 10^a formed with a cored-out recess 28 by a revolute coupling 29

and thence with the conduit 32, which bends upwardly to a point above the center of the furnace and then downwardly into the flared out open mouth 31, which is funnel-shaped and which as shown flares partly upwardly and partly downwardly although this forms no part of my invention herein.

The blower is preferably driven by a motor 34, the shaft of which carries a pinion 35 which is arranged to mesh with the gear 36 operating an oil pump 37. The base plate 38 of the housing 36^a of the gear 36 is slotted at 38^b and secured by bolts 38^a to a plate 31^a which is formed as part of the blower casing so that the pump can be shifted to disconnect the pinion 35 from the pump gear 36 as shown in Fig. 1, or to connect the gears as indicated in Fig. 2. The pump 37 is mounted on a bracket 37^a secured to the housing 36^a above mentioned.

A pressure gage 40 is provided for the pump as shown, and the exhaust or overflow from the pump taken off by the pipe 40^a. The oil is supplied to the pump through pipe 39^a and from the pump to the spray nozzle 41, projecting into the flaring opening 31 through a flexible hose pipe 42, or the like, or with iron pipe as desired.

When gas is used as a fuel, the pump is disconnected by sliding the pump base 38 along the base plate 31^a, thereby separating the gears 35, 36, which leaves the pump inactive. Should the gas supply fail, or for other reasons oil is desired to be substituted, in a moment's notice the oil pump can be connected and the oil delivered in a fine spray at the oil nozzle 41, where it is properly mixed with air from the blower.

Having thus described my invention, what I claim as new and desire to secure by Letters Patent is:—

1. The combination with a furnace having a fuel inlet, of a blower, and means for operating same to furnish a forced draft through said inlet, an oil pump operatively connected to said blower, and separate gas and oil conduits to said fuel inlet whereby either gaseous or liquid fuel may be utilized.

2. The combination with a furnace having a fuel inlet, of a blower, and means for operating same to furnish a forced draft through said inlet, an oil pump operatively

connected to said blower with means for disconnecting the same, and separate gas and oil conduits to said fuel inlet, whereby either gaseous or liquid fuel may be utilized.

5 3. The combination with a furnace having a fuel inlet, of a blower, and means for operating same to furnish a forced draft

through said inlet, an oil pump, with gearing intermediate the pump and blower, and means for shifting the oil pump to disconnect the gearing, and separate gas and oil conduits to said fuel inlet, whereby either gaseous or liquid fuel may be utilized. 10

JOSEPH E. HAUSFELD.
